IMPROVEMENT IN COMBS.

EDWARD H. KNIGHT, OF WASHINGTON, DISTRICT OF COLUMBIA, ASSIGNOR
TO IGNATIUS RICE, OF NEW YORK CITY.

Letters Patent No. 60,197, dated December 4, 1866.

SPECIFICATION.

TO ALL WHOM IT MAY CONCERN:

Be it known that I, EDWARD H. KNIGHT, of Washington, District of Columbia, have made new and useful improvements in Combs; and I do hereby declare the following to be a full, clear, and exact description of the nature, construction, and operation of the same, sufficient to enable one skilled in the art to which it appertains to construct and use the same, reference being had to the accompanying drawing, which is made part of this specification, and in which—

Figure 1 is a perspective view of my improved comb.

Figures 2, 3, 4, and 5, are sectional views, showing modifications of the mode of applying the elastic metallic band.

Figures 6 and 7 are partial views of combs, showing modifications in the mode of attaching the elastic metallic band.

The same letters in the corresponding figures refer to like parts.

The invention relates chiefly to the application to a comb of an elastic band of metal. It is especially but not exclusively intended for children's round combs, which are thereby strengthened and maintained in position, being assisted in returning to their normal form after being bent by the action of the spring. The round comb is necessarily elastic, and by means of this added spring it may be formed of material having no innate elasticity but possessing mere flexibility, which latter quality, while it permits it to be bent without injury, does not induce it to return to its normal position with sufficient force. Many materials are pliable and flexible without being sufficiently elastic for this purpose, and such may be utilized by the use of a spring, which confers the required elasticity upon them. Some kinds of wood may be used, for instance, and the metallic band will strengthen and support them, and prevent warping out of shape.

The invention is not confined to any particular mode of attaching the band to the comb. In fig. 1 the band is shown riveted to the comb, the ends of the band embracing the end of the comb proper; fig. 2 is essentially the same, but the band is inserted into a groove in the side of the comb; fig. 3, the band is on the outside, like fig. 1; fig. 4, it is completely buried in the material of which the comb is made; figs. 5 and 7, it is fastened to the comb by a small wire or wrapping, which may be of an ornamental character and fastened by solder or otherwise; fig. 6, the clasps which fasten the band to the comb are attached to the band and are bent around the back of the comb and between the teeth. A in each case is the metallic band, and B the comb proper; C rivets; D attaching wires or straps. The mode of attaching the band to the comb proper will depend to some extent upon the material of which the latter is formed; with brittle material it may be imprudent to weaken by rivet holes. The fastenings may be so near together as to maintain the comb in a tolerable degree of integrity even when the comb proper has been cracked across. When the material is such as may be pressed into shape, it may be made to enclose the elastic band, as shown in fig. 4 by the section lines.

I do not claim broadly the attachment of an elastic band to a comb. I claim as my invention—

1. The combination, with a comb, of a strip of metal imbedded or inserted in the back of the comb, substantially as hereinabove set forth.
2. The combination, with a strip of metal, A, and the back of a comb, of the bands or hooks D, substantially as and to the effect set forth.
3. Returning the strip of metal A over the ends of the comb, substantially as hereinabove set forth.

EDWARD H. KNIGHT.
